UNITED STATES PATENT OFFICE.

FREDERIC W. HILLARD, OF TOTTENVILLE, NEW YORK.

TYPE-WRITING MACHINE.

No. 923,121.

Specification of Letters Patent.

Patented May 25, 1909.

Original application filed August 25, 1896, Serial No. 603,845. Divided and this application filed November 18, 1904. Serial No. 233,366.

To all whom it may concern:

Be it known that I, FREDERIC W. HILLARD, a resident of Tottenville, in the county of Richmond and city and State of New York, have invented certain new and useful Improvements in Type-Writing Machines, of which the following is a specification.

My invention is an improvement in type-writing machines, its primary aim being to produce a typewriter with the double advantage of printing in sight and with a whole type ring in which to pivot the type bars.

Typewriters heretofore constructed are divisible into two classes, viz., those in which the printing is done out of sight but which are provided with whole type rings for the type bars, and those which print in sight but which are only provided with arcs of type rings for the type bars. My invention combines the advantages of each of the two classes without their disadvantages. As illustrating my meaning, the circle in which the type bars are pivoted, may be considered as comprising the four quadrants, or 90 degree arcs, thereof; and in my machine the type bars are pivoted in all four such arcs, while in many other visible writing machines, heretofore in use, the whole set of type bars is comprised within two, and usually less than two, such arcs. For convenience of description it may be said that my set of type bars comprise four series of bars, viz., those pivoted in the quadrant at the top of the circle, those pivoted in the two quadrants the one at the right and the other at the left hand side of the circle, and those pivoted in the quadrant at the bottom of the circle; the whole set thus being comprised in four arcs of 90 degrees each. It is convenient to thus classify the bars, as those in each arc lie normally in different relation to the remainder of the machine from those of all the other arcs, strike in different directions to the platen and bear different relations to their key levers.

My invention also comprises the detail mechanism for embodying my invention. Much of this detail which is novel is applicable to typewriters heretofore in use. I accordingly show in the accompanying drawings, 1st, my improved typewriting machine with the mechanism illustrated in detail, and, 2nd, many novel features of mechanism, which are applicable to other type-

writers, applied to my said improved type-writing machine.

Among the important features of the invention described and claimed, may be mentioned the following.

1st. A type-bar plate, which in the particular machine illustrated herein is shown as an unbroken type-ring, between the platen and the operator, with a central opening in the visual line between the operator and the printing point and the nearby portion of the platen.

2nd. A paper-carriage which is shiftable to a plurality of printing positions at different levels, in combination with means for lifting the platen into view above any printing position and relatively to a type-bar support, as for inspection and correction of the type-written work, and in combination with a series of type-bars on said support.

3rd. A movable or vibratory inking-ribbon between the type-bar support and the platen, arranged and adapted, in combination with the described printing mechanism, to be brought over the printing point at the moment of impact of a character and to then be retracted away from the platen and out of the visual line between the operator and the printing point.

4th. The combination with a series of type-bars, of two series of connecting wires or links extending in different directions, the one series of links extending in a direction substantially parallel with the normal positions of their type-bars and the other series extending upwardly from the key-levers, and bell-crank levers between the two series of links, having prolonged axes extending transversely of the machine, each bell-crank having an arm practically in line with its type-bar and connected thereto by one of the type-bar links, and also having an arm practically in line with its key-lever and connected therewith by a key-lever link; so as to connect a type-bar in one position transverse of the machine with a key-lever in another position transverse the machine.

5th. Type-bars mounted on the type-bar support above the line of vision, connected to rock-shafts or bell-cranks having prolonged axes extending transversely of the machine, in combination with connecting-wires or links which are substantially parallel with the type-bars and attached thereto and to the inner ends of the rock-shafts.

above the line of vision, and other connecting-wires or links which are attached to key-levers to one side of the visual line and to the outer ends of the rock-shafts; so that the 5 type-bars pivoted above the line of vision may be connected to key-levers on one side or other of the machine, thus leaving the visual line between the operator and the platen wholly unobstructed by the key-lever 10 links at and in the vicinity of the printing point; the said upper series of type-bars and their links lying in the central transverse section of the machine, with the corresponding series of key-levers and their links spread 15 apart right and left and occupying a wider transverse section of the machine.

6th. Two key-levers connected to the same type-bar by slotted connections, one of the key-levers being connected with the single-spacing mechanism and the other with the double-spacing mechanism, and a third lever connected with the same type-bar and with the spacing mechanism.

In the accompanying drawings which form 25 a part of this specification, Figure 1. is a detail side elevation of my type writing machine, some of the parts being cut away in longitudinal section to more clearly show the mechanism of the machine. Fig. 2. is a 30 side elevation in the same position as Fig. 1. but with all the parts in place, excepting that some details are omitted. Fig. 3. is a 35 plan view of the machine. Fig. 4. is a front view, showing the machine as it appears to 40 the operator. In this view the mechanism for feeding the inking ribbon is omitted. Fig. 5. is a detail view of the platen shifting mechanism showing the positions of the 45 parts in their normal state in full lines, and the positions of most of the parts in their 50 two shifted states in dotted lines. Fig. 6. is a detail view of a rock shaft which connects the same type bar with three levers, and of the connecting wire between the rock 55 shaft and the type bar, and the two slotted connecting wires which extend to two key levers, and the wire which forms the connection 60 between the type bar and the carriage propelling power. Fig. 7. is a longitudinal section of a side elevation of some of the 65 parts shown in Fig. 1, showing the type bar, rock shaft and connecting wires illustrated in Fig. 9, as they appear in the machine. Figs. 8, 9 and 10 are enlarged detail views of 70 the type-bar and vibratory platen shown in Figs. 5 and 7. Fig. 8 is a view of the platen and type-bar in the central printing position, shown in Fig. 7, with the type bar at 75 the printing point, corresponding to the full line position of Fig. 5. Fig. 9 shows the platen shifted to the lower printing position, corresponding to the lower position thereof shown in dotted lines in Fig. 5, and the type 80 bar at the printing point. And Fig. 10 is a 85 similar view with the platen in its upper

printing position, corresponding to the upper dotted line position of Fig. 5, with the type-bar at the printing point.

Fig. 1 shows a sectional view of the base frame, 1. Extending in a perpendicular direction from the back portion of the base frame are the brackets 2 for the carriage guide rail 3 and the parts mounted on the guides rail. The principal parts which are mounted on the guide rail are the paper carriage 4, the rack 5, and the carriage shifting frame 6. At the front of the machine is placed the key board. Intermediate between the paper carriage and the key board the type bar plate 7 is mounted on the base 70 frame of the machine. The type bar plate inclines backward at a slight angle from the perpendicular plane. Fig. 1 shows a sectional view of the type bar plate, taken on the line Y Y of Fig. 3. The type bar plate 75 comprises a ring with type bars mounted concentrically thereon and pivoted in the usual manner so that they can all strike through the central opening in the ring to a common printing center on the platen 8. 80 The type bar plate is inclined slightly backward from the perpendicular in order that the line of vision between the operator on the machine and the printing center may be 85 clear and unobstructed. There is a central 90 opening through the casing 9 which guards the type bar plate. Through this central opening the writing on the platen may be clearly seen by the operator as soon as each 95 letter has been printed. This is clearly 100 shown in Fig. 4, which shows the printing as it appears to the operator. By this arrangement I am enabled to secure a whole type 105 ring in which to pivot the type bars, and I also secure the additional advantage of 110 printing in sight. Heretofore type writing machines have either been constructed to print out of sight or else the type bars have all been mounted in only one half of the type 115 ring. By my present construction I have 120 secured the advantages of both classes of machines without their disadvantages.

By an inspection of Fig. 4 of the drawings it will be seen that, although there are type-bars mounted entirely around the type-ring, and some of them directly above the visual 125 between the operator and the platen, there are no key-lever connecting-wires in view of the operator as he looks through the open space in the casing 9 toward the platen. This is due to the use of the two series of connecting-wires 18 and 22 and the bell-crank levers 21 having prolonged axes extending transversely of the machine, by means of which the upper central series of 130 type-bars is connected to key-levers at the right hand and left hand sides of the machine, whose upwardly extending connecting-wires 22 lie within the casing and wholly to one side or the other of the opening 135

therein through which the operator views his work.

In order to fully carry out my design of machine I use the following additional features. The inking ribbon 10 is mounted on the spools 11 and is fed from one spool to the other by the ratchets 12 and the pawls 13, which are connected with the dog carrying rocker frame 14. The ribbon is fed when the rocker frame is operated. The ribbon passes through the ribbon guide or holder 15. The ribbon guide is pivoted to an arm, and at its lower end is connected by a connecting wire with the rocker frame 14. When a type key is depressed the rocker frame is rocked and the ribbon guide with the ribbon vibrated to the printing center; and when the key is released the ribbon guide and ribbon are vibrated away from the platen again out of the line of vision of the operator, as is clearly shown by the arrow in Fig. 1 and as is shown in Fig. 4. In Fig. 4 the ribbon is shown in normal place below the line of writing.

The type bars are connected with the key levers 17 and are operated when the key levers are depressed. Owing to their positions in the type ring they cannot be connected to the key levers in the ordinary manner by simple connecting wires. The method by which I connect them is as follows: I attach a connecting wire 18 to each type bar in the usual manner. These connecting wires extend in a direction substantially parallel with the direction of the type bars when at rest. At their front ends they are attached to the inner ends of the bell crank levers 19. To the outer ends of the bell crank levers are attached a second set of connecting wires 20 or 22; and these latter wires are extended downwardly and connected with the key levers, in the usual manner. As above stated I have also provided means for keeping the space in front of the printing center on the platen clear of connecting wires so as not to obstruct the view of the writing. In order to accomplish this I have substituted rock shafts 21, (see Fig. 6) in place of the bell crank levers. By attaching the connecting wire 18 to the end of the rock shaft directly above the line of vision and the connecting wire 20 to the other end of the rock shaft I remove the connecting wire 20 out of line of vision between the operator and the platen. For this purpose the other connecting wire 20 and the wire 22 should be omitted.

From an inspection of Fig. 1 of the drawings it will be seen that the type-bar connecting wires 18 are shorter than the type-bars 23 and hence the rock-shafts 21 are located longitudinally of the machine in positions opposite the shanks of the type-bars and between the point of their pivotal connection to the type-bar support and their type-heads. Hence each rock-shaft connected to a type-

bar in the upper half of the type-bar ring (and having its inner rocker-arm in line with its connected type-bar) must have its axis prolonged to a point outside of or beyond the extreme right hand or left hand type-bars at 70 the sides of the ring, so that the connecting-wire 20 or 22 which extends upwardly from one of the key levers at the side of the machine may connect with the outer rocker-arm of the rock-shaft without interfering 75 with the type-bars at the sides of the type-bar ring. Hence also the key-lever system must be wider than the type-bar system, as it is clearly seen to be in Fig. 4 of the drawings. The casing 9 is, however, made wider 80 than the key-lever system so as to inclose and protect all of the connecting-wires 18, 20 and 22 and the several rock-shafts 21, as well as the system of type-bars and key-levers.

The arrangement of the type keys in the 85 key board is that of the Remington Standard typewriter, excepting that in the next to the top row of keys I have placed a row of double spacing keys which are connected with the type characters which are frequently terminal characters. The row of double spacing keys is distinguished from the remainder of the keys by being black with white letters, while the other keys are white with black letters. 95

In my present construction I show an improved form of connecting two keys with the same type bar, and one of the keys with the single spacing mechanism and the other key with the double spacing mechanism. This 100 improvement consists in a third wire which is connected to the same type bar and to the spacing mechanism. Its object is to bring the force of the carriage main spring to bear on the type bar to start it back to normal position after the printing has taken place, as will be hereinafter fully described. The construction of this device is shown in Figs. 6 and 7, in which the two slotted connecting wires 20 20 are connected with the same type 110 bar 23 through the rock shaft 21 and the connecting wire 18, and one wire 20, is connected with a single spacing key and the other 20, with a double spacing key; and there is a third wire 22, connected at one end to the 115 type bar 23, through the rock shaft 21, and the wire 18, and connected at its other end with the spacing mechanism through the key-less lever 24.

The paper carriage 4, is mounted at its 120 rear edge on the guide rail 3 and is fastened to the rail by grooves in the carriage and corresponding grooves in the guide rail, and bearing balls in the grooves. The carriage is free to travel on the rail on the bearing 125 balls, from one end of the rail to the other, for letter spacing. At its front edge the carriage is provided with the roller 25 which rests and travels with the carriage on the front rail 26 (see Figs. 1 and 5). It can be 130

lifted off from the front rail, and the carriage raised for inspection of the writing, etc., by taking hold of the front of the carriage and lifting it. Fig. 1 shows the carriage in its 5 normal position, and Fig. 2 shows it in its raised position. The arrows in Figs. 1 and 2 show the line of vision. When the carriage is raised the guide rail is revolved with the carriage, the two being held together and 10 revolved together on their axes by the bearing balls 27. A sectional view of the bearing balls and their grooves is shown in Fig. 7. There are two bearing balls on the top of the 15 guide rail, and one at the bottom of the rail intermediately between the two on the top of the rail. The front carriage rail is also pivoted concentrically with the guide rail 3 and the carriage 4. The front rail is supported by the arms 6 of the shifting frame. 20 The carriage is shifted from its normal position in lower case to its shifted position in upper case by depressing the shifting frame 6 and the front rail 26. The carriage is also shifted to a third position for printing special 25 characters, which are carried on certain of the type bars, by lifting the front rail.

A detail of the mechanism for shifting the front rail and the carriage down to upper case and for lifting them to special case is 30 shown in Fig. 5. The shift key 28 is connected with the shift frame 6 by means of the link 29. The carriage is held in its normal position against gravity by means of the spring 30 and the lever 31. The pin 32 prevents 35 the spring 30 and the lever 31 from raising the shift frame higher than its normal position. When it is desired to lift the shifting frame and the carriage to their upper position the spring 33 and the lever 34 assist in overcoming the weight of the carriage. Hence the carriage can be easily 40 lifted to shift it to special case. There is only one shift key for all three cases. By depressing the shift key the carriage is lowered to upper case, and by lifting the shift key the carriage is raised to special case, as 45 shown in dotted lines in Fig. 5. In machines heretofore invented with three types on a bar two shift keys have been provided, 50 one for shifting to capital letters and one for shifting to figures and other characters. I accomplish the same results by the use of one key by depressing the key for one case and lifting it for the other case.

The shift key 28, is connected with the shifting frame 6 by the connecting link 29 (see Fig. 5). At the lower end of the link 29 there is a slot, and on the shift key lever 55 there is a pin 44 which works in the slot. This arrangement enables the roller 43 to disengage the lever 37 from its obstructive engagement with the prong 38, before the shifting of the carriage is begun.

In order to insure good alinement it is essential 60 that the carriage be secured against

any loose movement on the guide rail. This is effected by the grooves in the rail and the bearing balls 27 in the grooves. The two bearing balls on the top of the guide rail 3, rest in the groove in the top of the rail. 70 Corresponding grooves are provided in the carriage frame 4, which rests on top of the two bearing balls. On the under side of the guide rail there is one bearing ball which rests in the groove in the bottom of the rail. 75 Below the ball in the bottom groove is a grooved casing 45, which holds the ball in the groove in the bottom of the rail and prevents it from escaping out of the groove. The carriage frame 4, and the lower casing 45, and 80 the bearing balls 27, and the guide rail 3, are all fastened together by the rack supporting clamps 46 46, which encircle the carriage frame and the casing 45. The rack clamps 46, can be adjusted by the adjusting screws 85 47 47, so as to take up any looseness of the carriage on the guide rail.

My present escapement comprises the rack 5, and the rocker frame 14, with its two reciprocating dogs 65 and 70. The front dog 90 65 normally engages with the rack. Upon depression of a key the front dog is disengaged from the rack and the rear dog 70, engaged therewith. Mounted on the base of the machine is the frame 73, which carries 95 the roller 74. The roller 74 acts as a cam for spacing the dog 70, backward while it is being brought into engagement with the rack. Upon depression of a key the rack is first disengaged from the dog 65, and under the 100 impulse of the main spring (which is contained in the spring barrel 75, and is connected to the carriage by a connecting band and the hook 76, in the usual manner) the carriage starts forward. The carriage then 105 feeds forward until the rack comes into contact with the dog 70, when it is cammed backward again with the dog by the roller 74, until the key is fully depressed, as is fully described in my said Patent, Number 110 554,874. The bevel faced wing 77, on the dog 70, engages with the cam roller to cam the dog backward. The dog 70 is rocked forward far enough to nearly but not quite bring the wing 77 to the rearmost part of the 115 roller 74. If it should be brought any farther forward the main spring could not disengage the dog 70, from the rack, but so long as the wing is in engagement with the roller behind the pivotal line of the roller the pull 120 of the main spring tends to disengage the dog 70, from the rack and to reengage the dog 65, therewith.

Such of the type bars as have two type keys connected with them (Figs. 6 and 7) one 125 for single spacing and the other for double spacing, have slotted connecting wires, and therefore the force of the main spring could not be brought to bear to return them to normal position unless some other means 130

were provided for that purpose. For such type bars I have provided other connecting wires 22 which are connected with keyless levers 24. The connecting wires 22 are not slotted, and consequently the keyless lever 24, connected with a type bar is operated for printing. The keyless levers 24, are connected with the spacing mechanism and must be lifted when the rocker frame is 10 turned to normal position, and hence the type bars connected with the keyless levers are started back to normal position by the main spring through the keyless levers and the connecting wires 22.

15 The key-levers are fulcrumed in the base-frame to the rear of the type-bar pivots, and extend under the carriage to the rear of the machine, where the universal bar rests over them.

20 The operation of the machine is as follows: When a key is depressed its key-lever is rocked on the fulcrum bar and the rear end lifted, thus rocking the universal bar up and the connected rocker-frame forwardly so as 25 to disengage dog 65 from the rack and engage dog 70 therewith, and to simultaneously vibrate the ribbon guide 15 to the platen so as to throw the printing ribbon against the surface to be written on. By

30 the same movement of the key the connected type-bar is simultaneously thrown against the platen and the printing thus effected.

If a lower case letter is to be printed no additional operation is required as the platen 35 is normally held in its intermediate printing position and the central type character on the type-bar then alines therewith. But if a capital letter is to be printed the capital letter shift key must first be depressed so

40 as to lower the platen to its lowest printing position where it is in alinement with the lowest type-character on the bar; while if one of the special case characters is to be printed the shift-key must be lifted up so as

45 to bring the platen to its highest printing position where it will aline with the highest or special character on the type-bar.

Since the platen, in shifting from one 50 printing position to another at a different level, oscillates about a relatively fixed pivot on the carriage, and in order that the type-characters shall register with the platen in each of its printing positions (meaning thereby that they shall coincide therewith

55 throughout the extent of their printing faces, or in the technical language of the trade be "on their feet"), it is necessary to curve the faces of the type relatively to each other so that they will correspond with the

60 curvature of the movement of the platen from the one printing position to another. This oscillatory movement of the platen to its three printing positions at different levels is clearly illustrated in Fig. 5 and in Figs. 8, 65 9 and 10. The corresponding inclination of

the printing-faces of the type toward each other is shown in Figs. 1 and 7, and in Figs. 8, 9 and 10.

Figs. 8, 9 and 10 are enlarged positional views of the platen 7 and one of the type-bars 23, in the three printing positions of the platen and with the type-bar at the printing-point. In Fig. 8 the central printing-character *a* of type-head 23^a, which is a lower case letter, is at the printing-point 8 and registering thereat or on its feet at the platen, the platen being in its normal central printing position. In Fig. 9 the carriage 4 has been shifted in an oscillatory manner about its guide-rail 3 as an axis, swinging the front-rail 26, the carriage-roller 25 and platen 7, downwardly to its lower, or capital letter, printing position, where the capital letter *B* is shown at the same printing-point 8 and registering thereat or on its feet at the platen. Fig. 10 shows the platen elevated, by an oscillatory movement of the carriage 4, front-rail 26 and carriage-roller 25, to its upper or special case printing position, with a figure or other special case character *c* at the same 90 printing point 8 and also registering thereat, or on its feet at the platen. The printing-face of each character *a*, *b*, *c*, is of course curved, as usual, to conform to the curvature of the periphery of the platen itself; but the 95 printing-faces are also curved or inclined relatively to each other, as shown, so as to correspond with the curvature of the oscillatory movement of the platen from one printing position to another, and this latter 100 curvature or inclination I believe to be novel, and so claim it. Such relative curvature of the printing-faces is of advantage in enabling me to simplify the platen shifting mechanism.

This application is a continuation and division of my previous application Serial Number 603,845, filed August 25th, 1896, and is filed in pursuance of a requirement of division of the Patent Office.

I do not in this application make any claim 110 or claims to the construction of the type bars with a plurality of types thereon, having their printing faces inclined inwardly toward each other so as to register with a pivotally mounted platen in each of its printing positions as such construction of the type bars is claimed in my other application serially numbered 469333, filed Dec. 26, 1908.

What I claim and desire to secure of the United States by Letters Patent is:

1. In a type-writing machine, the combination of a printing platen, a type bar plate mounted in front of the platen between the operator and the platen and having a central opening in the line of vision between the operator and the platen, a series of type bars mounted on the type bar plate around the central opening and arranged to strike through the central opening to the platen, and means for lifting the platen into view 125

above the type-bar plate, substantially as described.

2. In a type-writing machine, the combination of a printing platen, a type ring 5 mounted in front of the platen in a plane oblique to the horizontal plane of the machine and having a central opening in the line of vision between the operator and the platen, a series of type bars mounted concentrically on the type ring and arranged to 10 all strike through the central opening to the platen, and means for lifting the platen into view above the type ring, substantially as described.

15 3. In a type-writing machine, the combination of a printing platen, a type bar plate mounted in front of the platen between the operator and the platen having a central opening in the line of vision between the 20 operator and the printing center at the platen, a type bar mounted on the type bar plate above the said line of vision, a rock shaft mounted above said line of vision, means for connecting the rock shaft with the 25 type bar, and a connecting wire extending downwardly from the rock shaft to a key lever at one side of the said line of vision, substantially as described.

30 4. In a type-writing machine, the combination of a printing platen, a type bar plate mounted in front of the platen between the operator and the platen having a central opening in the line of vision between the operator and the printing center at the 35 platen, a series of type bars mounted on the type bar plate above the said line of vision, a series of rock shafts mounted above the said line of vision, means for connecting each rock shaft with a type bar, and a connecting 40 wire extending downwardly from each rock shaft to a key lever at one side of the said line of vision, substantially as described.

45 5. In a type-writing machine, the combination of a printing platen, a type bar plate mounted in front of the platen in a plane oblique to the horizontal plane of the machine and having a central opening in the line of vision between the operator and the platen, a series of type bars mounted on the type bar 50 plate around the central opening arranged to strike through the opening to the platen, a series of connecting wires attached to the type bars at one end and extending in a direction substantially parallel to the said line 55 of vision, a series of bell crank levers to which the said connecting wires are attached at their other ends, and another series of connecting wires attached by one end to the said bell crank levers and by their other ends to a 60 series of key levers, substantially as described.

65 6. In a type-writing machine, the combination of a type bar, two key levers, means for independently connecting both key levers with the said type bar by slotted con-

nections whereby each key lever independently operates the same type bar to print the same character, spacing mechanism, means for connecting one of the key levers therewith for uniform or ordinary spacing, 70 means for connecting the other key lever with the spacing mechanism to effect double or extra spacing, and a third lever connected with the said type bar and with the spacing mechanism, substantially as described. 75

7. In a type-writing machine, the combination of a type bar, a rock shaft operatively connected therewith, two key levers, means for independently connecting both key levers with the same rock shaft by slotted connections whereby each lever independently operates the same type bar to print the same character, spacing mechanism, means for connecting one of the key levers therewith for uniform or ordinary spacing, 80 means for connecting the other key lever with the spacing mechanism to effect double or extra spacing, and a third lever connected with the 85 said rock shaft and with the spacing mechanism, substantially as described. 90

8. In a type-writing machine, the combination of a printing-couple comprising a platen and a type-ring mounted in front of the platen and having a central opening in the line of vision between the operator and the platen, a series of rearwardly-striking type-bars mounted concentrically on the type-ring, each provided with a plurality of types rigidly secured thereto and all arranged to strike through the central opening to the 100 platen, a series of keys to operate the type-bars, and a key and connections for moving the platen to a plurality of printing-positions at different levels.

9. In a typewriting machine, the combination of a printing-couple comprising a support for a series of type-bars and a platen, a curved series of rearwardly striking type-bars mounted on said support, a series of key-levers, and an intermediate series of bell-crank levers connected to the type-bars and to the key-levers, the bell-crank having prolonged axles which extend transversely of the machine, and each bell-crank having one arm which is practically in line with its connected 110 type-bar and having another arm which is practically in line with its connected key-lever. 115

10. In a typewriting machine, the combination, with the key-levers, of a printing couple comprising a platen and a support for a series of type-bars, the type-bars being pivotally supported in front of the platen and adapted to strike on the front side thereof and some of them being pivoted above and others below the horizontal plane at which their types strike the platen, means for at will moving one member of said couple relatively to the other to a plurality of printing positions at different levels, two or more characters rig- 125 130

idly secured to each type bar and operative connections between each type-bar and its corresponding key-lever.

11. In a typewriting machine, the combination of two coöperating members, one comprising a platen and the other a support for a series of type-bars, type-bars pivotally supported in front of the platen and adapted to strike on the front side thereof and some of them being pivoted above and others below the horizontal plane at which their types strike the platen, means for at will moving one of said members relatively to the other to a plurality of printing positions at different levels, key-levers, levers operated by the key-levers, and link connections between the latter levers and the type-bars.

12. In a typewriting machine, the combination of a platen constructed and arranged to be moved to a plurality of printing positions at different levels, means for at will so moving the platen, key-levers, a series of type-bars pivotally supported in front of the platen, some of the type-bars above and others below the horizontal plane in which their types strike the platen, two or more characters rigidly secured to each type-bar and operative connections between each type-bar and its corresponding key-lever.

13. In a typewriting machine, the combination of a printing-couple comprising a support for a series of type-bars and a platen, a curved series of rearwardly striking type-bars mounted on said support, a series of key-levers extending under the type-bar support, the width of the series of type-bars being less than the width of the series of key-levers, and an intermediate series of bell-cranks having prolonged axes which extend transversely of the machine, each bell-crank having an arm which is practically in line with its type-bar and is connected thereto by a link, and also having an arm which is practically in line with its key-lever and is connected thereto by a link.

14. The combination of an endwise-movable carriage, a platen mounted thereon and movable transversely to the line of travel to a plurality of printing positions at different levels, means for at will so moving the platen transversely, a series of key-levers, a series of type-bars pivoted in front of the platen, some below and others above the horizontal plane at which their types strike the platen, each type-bar swinging on a single pivotal center, and normally inclined away from the platen toward the front of the machine, a plate arranged in front of the platen and on which said type-bars are pivoted, two or more characters rigidly secured to each type-bar and operative connections between each type-bar and its corresponding key-lever.

15. In a typewriting machine, the combination with the platen, of a curved series of radially striking type-bars, a support for said

type-bars mounted in a plane oblique to the horizontal plane of the machine, a series of rock-shafts provided with arms at an angle to each other arranged obliquely at different levels, a series of links connected at one end 70 to the short arms of the type-bars and at their other ends to one set of arms on the rock-shafts, and a second series of practically parallel links connected at one end to the key-levers and at their other ends to the other set 75 of rocker-arms.

16. In a typewriting machine, the combination of a platen constructed and arranged to be moved to a plurality of printing positions at different levels, a series of type-bars 80 pivoted in front of the platen and adapted to strike on the front side thereof, some of the type-bars being pivoted above and others below the horizontal plane at which their types strike the platen, key-levers, levers 85 operated by the key-levers, and link connections between the latter levers and the type-bars.

17. In a typewriting machine, the combination with the platen, of a series of rearwardly-striking type-bars, a series of key-levers, a series of links which are attached to the type-bars and extend longitudinally thereof, a series of links which are attached to the key-levers and extend upwardly therefrom, and a series of bell-cranks having prolonged axes extending transversely of the machine, and each bell-crank having one arm which is practically in line with its type bar and engaged therewith by a type-bar link 100 and having another arm which is practically in line with its key lever and engaged therewith by a key-lever link.

18. The combination of a platen movable endwise and transversely to printing positions located in a plane oblique to the horizontal plane of the machine, means for at will so moving the platen transversely, a series of type-bars pivoted in front of the platen and each swinging on a single pivotal 110 center and having more than one character thereon, a support arranged obliquely to a horizontal plane and on which said type-bars are pivoted, a series of horizontally-disposed key-levers pivoted in the rear of the 115 type bar pivots and extending forward under the platen and type-bars, and operative connections between each key-lever and its corresponding type-bar.

19. In a typewriting machine, the combination of a platen, a series of pivoted type-bars each provided with a plurality of types rigidly secured thereto, said type-bars being pivoted in an arc which lies in a plane oblique to the horizontal plane of the machine 125 and being constructed and arranged to strike between the top and front of the platen, a shift-key, and connections between said shift-key and said platen constructed and arranged to enable the platen to shift from 130

one printing position to another at different levels in a plane coincident with or parallel to the oblique plane in which the type bar pivots are situated.

- 5 20. In a typewriting machine, the combination of a platen, a series of pivoted type-bars each provided with a plurality of types rigidly secured thereto, said type-bars being pivoted in an arc which lies in a plane oblique to the horizontal plane of the machine, and being constructed and arranged to strike between the top and front of the platen, a shift key, and connections between said shift key and said platen constructed and arranged to enable the platen to be shifted transversely from one position to another located in a plane parallel to the said oblique plane in which the type-bar pivots are situated.
- 10 21. In a typewriting machine, the combination of a platen, a series of pivoted type-bars each provided with a plurality of types rigidly secured thereto, said type-bars being pivoted in a curved line which lies in a plane oblique to the horizontal plane of the machine and being constructed and arranged to strike between the top and front of the platen, some of said type-bars being pivoted above and others below the point at which their types strike the platen, a shift-key, and connections between said shift-key and said platen constructed and arranged to enable the platen to shift transversely from one position to another in a plane parallel to the oblique plane in which the type-bars are situated.

- 15 22. The combination of the platen movable endwise and also transversely to printing positions in a plane oblique to the horizontal plane of the machine, means for at will moving the platen transversely, a series of type-bars pivoted in front of the platen, the pivots of the type-bars being situated in one or more planes oblique to a horizontal plane and each type bar having more than one character thereon, a series of horizontally disposed key levers pivoted in the rear of the type bar pivots and extending forward under the platen and type-bars, a series of angular levers or bell cranks pivoted below the type-bars and each operatively connecting a key-lever with its corresponding type-bar.

- 20 23. The combination of an endwise movable platen mounted to be shifted transversely to printing positions in a plane oblique to the horizontal plane of the machine, a series of pivoted type bars each having more than one character thereon, in front of the platen and normally lying inclined toward the front of the machine and arranged to strike downwardly upon the upper front quarter of the platen, a series of key levers pivoted in rear of the type bar pivots, a series of levers interposed between the type bars and key levers and operative connec-

tions between the interposed levers, key levers and type bars.

24. In a typewriting machine the combination of the platen, the type bars arranged to strike downwardly thereon, the key levers, the interposed levers or bell cranks arranged above the pivots of the type bars, and links extending from one end of the interposed levers downwardly to the key levers and from the opposite end thereof downwardly to the type bars.

25. In a typewriting machine, the combination of a platen, pivoted type-bars adapted to strike upon the platen at a point visible to the operators in front of a vertical plane passing through its axis, some of the said type-bars being pivoted above and others below the level of the point at which their types strike upon the platen, key-levers, levers operated by the key-levers, and link connections between the latter levers and the type-bars.

26. In a typewriting machine, the combination of an endwise traveling carriage, a platen wholly supported upon the carriage and shiftable obliquely independently thereof, and a series of type bars carrying each a plurality of types and arranged in front of the platen and adapted to strike upon the upper front side thereof.

27. In a typewriting machine, the combination of a printing-couple comprising a support for a series of type-bars and a platen, a curved series of rearwardly-striking radially striking type-bars mounted on said support, a series of bell-cranks, the axes of said bell-cranks being prolonged transversely of the machine and lying one above another and each bell-crank being provided with two crank-arms arranged thereon at an angle to each other, one arm of each bell-crank being attached to a key-lever and the other arm to a type-bar, a series of connecting-wires between the bell-cranks and key-levers and another series of connecting-wires between the bell-cranks and the type-bars.

28. In a typewriting machine, the combination of a printing-couple comprising a platen and a support for a series of type-bars, a curved series of rearwardly-striking radial type-bars pivotally mounted thereon, a series of key-levers extending rearwardly beneath the type-bars, a series of links which are attached to the type-bars and extend longitudinally thereof, a series of links which are attached to the key-levers and extend upwardly therefrom, the width of the system of key-lever links being greater than the width of the system of type-bar links, and bell-cranks having prolonged axes extending transversely of the machine from said key-lever links to said type-bar links.

29. In a typewriting machine, the combination of a platen, a series of pivoted type-bars each provided with a plurality of types

rigidly secured thereto, said type-bars being pivoted in an arc which lies in a plane oblique to the horizontal plane of the machine and being constructed and arranged to strike between the top and front of the platen, a shift-key, connections between said shift-key and said platen arranged and constructed to enable the platen to shift transversely from one printing position to another located in the plane parallel with the oblique plane in which the type-bar pivots are situated, a vibratory inking-ribbon between said type bars and the platen, and ribbon mechanism constructed and arranged to bring said ribbon over the printing point at the moment of impact of a character and to then retract it away from the platen and out of the visual line between the operator and the printing point.

30. The combination of an endwise-movable carriage, a platen mounted thereon and movable transversely to the line of travel and in a direction inclined to a horizontal plane, means for at will so moving the platen transversely, a series of pivoted, horizontally-dis-

posed key-levers extending under the carriage and to the front of the machine, a series of type-bars pivoted in front of the platen below the horizontal plane thereof and each of which swings on a single pivot-center, and normally inclined away from the platen toward the front of the machine, a support arranged obliquely to a horizontal plane and on which said type-bars are pivoted, two or more characters rigidly secured to each type-bar, operative connections between each type-bar and its corresponding key-lever, a vibratory inking-ribbon between said support and the platen, and ribbon mechanism constructed and arranged to bring said ribbon over the printing point at the moment of impact of a character and to then retract it away from the platen and out of the visual line between the operator and the printing point.
